UNITED STATES PATENT OFFICE.

FRANKLIN HILTON, OF MIDDLESBROUGH-ON-TEES, COUNTY OF YORK,
ENGLAND.

APPLIANCE FOR HEATING ROLLS OF ROLLING-MILLS.

SPECIFICATION forming part of Letters Patent No. 372,621, dated November 1, 1887.

Application filed April 27, 1887. Serial No. 236,382. (No model.) Patented in England July 17, 1886, No. 9,330.

To all whom it may concern:

Be it known that I, FRANKLIN HILTON, a subject of the Queen of Great Britain and Ireland, residing at Middlesbrough-on-Tees, in 5 the county of York, Kingdom of Great Britain and Ireland, have invented Improvements in Rolling-Mills, (which have been patented to me in Great Britain, dated July 17, 1886, No. 9,330,) of which the following is a specification.

Heretofore, in order to heat or warm up the rolls of rolling-mills to a proper working temperature, it has been usual to build coal or coke fires underneath the rolls over night, or to place 15 fires or red-hot ingots or masses of heated metal upon the fore plates of the rolls in close proximity thereto. These several means of heating or warming up the rolls, however, are open to serious objection. They are liable to cause 20 unequal expansion, owing to the heat being applied only locally. It results that with these means of heating the rolls are frequently injured, and in some cases, owing to the unequal expansion, are caused to burst.

The object of my invention is to heat or 25 warm up the rolls to a proper working temperature or maintain them at such a temperature in a regular and uniform manner, which I effect by the application of gas-jets caused 30 to play upon the whole length of the barrel portions of the rolls.

In carrying out this invention two or more lines of gas-jets may be employed, and the jets can be caused to play constantly, whether rolling 35 is being effected or not, the rolls being kept rotating slowly but constantly during the heating or warming process, as usual. One or more lines of jets may be applied midway between the pairs of rolls, and be arranged in 40 such a manner that the same can be brought into use only after the usual rest at end of the week, for the purpose of getting up the temperature in readiness for the commencement of another week's work. In such an arrangement 45 these jets can be quickly connected or disconnected by any suitable means, such as a flexible tube. The number of pipes and their position and arrangement will depend upon the requirements of particular applications, 50 and may be varied within wide limits, so long as there be a slow and uniform application of

heat by gas applied in such a manner that the heat is caused to spread quickly over the entire surface or length of the rolls, thus obviating unequal expansion.

Referring to the accompanying drawings, Figure 1 is an elevation, and Fig. 2 a transverse section, of a rolling-mill provided with apparatus according to this invention for heating or warming up the rolls.

a and *b* are the rolls, carried in standards or housings *c* in the usual manner.

d d are gas-pipes arranged longitudinally of the rolls, and each provided with burners, nipples, or orifices *d' d'*. These pipes *d d* are 65 supported at *e e*, as shown—viz., the pipe for top roll in hole through top riders and the bottom on the standards or housings *c*. *f* is a gas-supply pipe in connection with any suitable source of gas-supply, and which conveys 70 gas to pipes *d d*.

When the apparatus is in use, gas-jets from the burners, nipples, or orifices *d' d'* play upon the rolls, as indicated, throughout the whole length of their barrel portions.

g is a similar pipe to *d d*, with a row of gas-burners, nipples, or orifices, *g'*, whence jets can be directed between or near where the rolls meet or nearly meet. Said pipe is connected with the gas-supply pipe by a pipe, *h*, and flexible tube *i* in such manner that it may be readily removed after the rolls have been sufficiently heated to allow rolling operations to be conducted.

While heating the rolls they should be slowly 85 and constantly rotated, in order that heating and expansion thereof may take place uniformly. There may be more pipes such as *d* and *g*, if desired.

Figs. 3 and 4 illustrate a modification in 90 which there are four pipes *d d*—that is to say, one at each side of each roll *a* and *b*—these pipes being arranged in or approximately in the same horizontal planes as the axes of the rolls. With this arrangement rolling may take place 95 without removing any of the pipes.

What I claim is—

1. A rolling-mill provided with apparatus for heating or warming up the rolls to a proper working temperature or maintaining them at 100 such a temperature (or both) in a regular and uniform manner by means of gas-jets caused

to play upon the whole length of the barrel portions of the rolls.

2. In a rolling-mill, apparatus for heating or warming up the rolls to a proper working temperature or maintaining them at such a temperature, (or both,) comprising gas-supply pipes with two or more lines of burners, nipples, or orifices so arranged that jets may be directed therethrough so as to play constantly upon the whole length of the barrel portions of the rolls, whether rolling is being effected or not, and another or other pipe or pipes with one or more lines of burners, nipples, or orifices so arranged that jets may be directed midway, or thereabout, between the pair of rolls, said last-mentioned pipe or pipes being removable, substantially as described.

3. In a rolling-mill, the combination, with rolls *a* and *b* and means for supporting and driving same, of the hereinabove described

apparatus, comprising gas-pipes *d d*, provided with burners, nipples, or orifices *d' d'*, supply-pipe *f*, removable pipe *g*, (or pipes,) provided with burners, nipples, or orifices *g'*, for directing gas-jets between said rolls, and gas-supply connections *h i* to said removable pipe, all substantially as described, for the purpose specified.

In testimony whereof I have signed my name to this specification in the presence of two subscribing witnesses.

FRANKLIN HILTON.
